UNITED STATES PATENT OFFICE.

WILLIAM J. P. CLOAKEY, OF BRANTFORD, ONTARIO, CANADA.

DUST-COLLECTOR.

1,275,663.

Specification of Letters Patent. Patented Aug. 13, 1918.

Application filed January 5, 1918. Serial No. 210,538.

To all whom it may concern:

Be it known that I, WILLIAM J. P. CLOAKEY, a subject of the King of Great Britain, residing in the city of Brantford, 5 county of Brant, Province of Ontario, Canada, have invented certain new and useful Improvements in Dust-Collectors, of which the following is a specification.

This invention relates to means for separating the dust from dust laden air particularly adapted for use with street sweeping apparatus, and my object is to devise simple apparatus for that purpose which will possess great capacity for its size and 15 which automatically cleanses itself while in use.

I attain my objects by means of the constructions hereinafter described and illustrated in the accompanying drawings in 20 which—

Figure 1 is a horizontal section, partly broken away, of my improved dust collector; and

Fig. 2 a vertical section of the same.

25 In the drawings like numerals of reference indicate corresponding parts in the different figures.

In the drawings I illustrate a double form of the apparatus, but it will be understood, 30 however, that for small capacity one half only of the apparatus can be used.

Within an outer casing 1, which, at its lower part, forms a water tank, I locate a cylinder 2 into which the dust laden air is 35 driven by means of the fan 3, the exhaust pipe 4 of which is led into the end of the cylinder 2. Concentric with the cylinder is arranged a drum 5, the periphery of which is formed of a suitable screening material.

40 This drum is preferably rotatable, being adapted to turn on the flanges 6, which are supported from the exhaust pipes 4 or other suitable stationary parts. The ends of the drum are preferably imperforate and fit 45 close to the ends of the wings 7 secured to the exterior of the cylinder 2. These wings are preferably two in number and are arranged diametrically opposite one another. Each wing has its outer surface concentric 50 with the drum 5, and subtends an arc of periphery of about eighty degrees. These wings are preferably hollow for the sake of lightness and for a further purpose which will hereafter appear.

55 The drum has secured to its inner surface a series of longitudinal radial partitions 8,

which extend from end to end of the drum. The distance between any two of them is less than the length of the arc of the outer surface of either of the wings.

60

In the side of the cylinder 2 is formed a port 9, through which air passes from the interior of the cylinder after following the course which will be hereafter described. This port is located between the wings 7 and 65 preferably at the under side of the cylinder. Dust laden air issuing from this port thus first strikes the surface of the water in the bottom of the casing 1. Owing to the engagement of the partitions 8 and the wings 7, this air cannot at once be deflected upwardly to pass straight out through the top 70 of the drum, but is gradually allowed to pass upward as the pockets formed by the drum, the partitions and the wings are alternately 75 opened to the space below the wings and the space above the wings.

The partitions, being preferably of screen material, of course, permit a certain amount of air to pass upwardly at any time, but with 80 the construction described the dust laden air is so distributed as to make practically every part of the screen surface take its share of the work. The water level in the bottom of the casing is maintained at such 85 a height that as the drum is rotated not only are all parts of its periphery thoroughly washed, but each partition is in turn completely submerged and thoroughly washed. All the screen surfaces are thus auto- 90 matically cleansed, whereby they are maintained in effective working condition.

To increase the effectiveness of the apparatus, it is desirable that a certain quantity of water be beaten up with the dust laden 95 air before screening takes place. I therefore arrange within the cylinder 2 one or more rotary beaters 15. These beaters are connected with a shaft 10 passing through the cylinder and supported in suitable bearings. The outer end of the shaft is provided with a driving pulley 11. Any type of 100 rotary beater might be employed. I show, however, for this purpose disks 12 between which are secured the radial blades 13, which 105 blades, however, extend only part way from the circumference of the beater to the shaft. A large eye is formed in the outer disk or each beater. With the eye of the outer beater the exhaust pipe 4 of the fan communicates. The pipe preferably is made as close a fit in the eye of the beater as pos- 110

- sible without interfering with the free rotation of the beater. The beater discharges into the interior of the cylinder 2, and if only one beater is employed it will be allowed 5 to pass directly to the port 9. If, however, a second beater be employed, the cylinder will be divided by a partition 14, which partition is arranged to form a running fit in the eye of the second beater 15.
- 10 After passing through the second beater, the air passes into the interior of the cylinder 2 and thence out through the port 9. As before stated, water is introduced to be beaten up with the air in the beaters. To 15 the outer beater this water is preferably conveyed by means of the sleeve 16 suitably fitted about the shaft 10 and connected by means of a pipe 17 with a suitable source of water supply. Holes 18 are formed in the 20 sleeve 16 communicating with the interior of the first beater. Water may be conveyed to the interior of the second beater by making the inner part of the shaft 10 hollow and providing it with holes communicating respectively with the interior of the second beater and the interior of the sleeve 16.
- A very thorough mingling of the water and dustladen air is thus obtained, the spray 25 of water in the interior of each beater being practically atomized by the action of the beaters and brought into very intimate contact with the dust carried by the air. The work of the screen surfaces is thus materially lightened and the capacity of the apparatus 30 for its size made much greater than would be the case without the use of the beaters. The drum, for the purposes of rotation, has a sleeve 19 secured to one end provided with a sprocket wheel 20.
- 35 For great capacity, the arrangement described may be duplicated at each end of the apparatus. It will be understood, of course, that various changes may be made in the details of construction without departing 40 from the spirit of my invention.
- The dusty air is forced by the pump 3 into the exhaust pipe 4, which leads through the 45 end of the cylinder 2 and communicates with the eye of the rotary beater 15. In the beater the air is intimately mixed with a spray of water, which is introduced through the sleeve 16. The mixture of air, dust and water then passes to the eye of the second beater 15, if a second beater be employed, 50 and is there beaten up with a further quantity of water. After passing the second beater, the air passes from the port 9 in the cylinder 2 and strikes the surface of the water in the bottom of the casing 1. Owing 55 to the engagement of the partitions 8 and the wings 7, this air cannot at once be deflected upwardly to pass straight out through the top of the drum, but is gradually allowed to pass upward, as the pockets formed by the 60 drum, the partitions and the wings are al-

ternately opened to the space below the wings and the space above the wings. The air finally escapes through the screened surfaces leaving the dust behind, which dust is washed off as the drum is rotated in the manner hereinbefore described. 70

What I claim as my invention is:—

1. In a dust collector, the combination of a rotatable screen drum having radial longitudinal partitions arranged therein extending from the periphery part way toward the center; a stationary dusty air conveying cylinder about which the screen drum rotates; and a plurality of wings connected to and extending lengthwise of the cylinder 80 having arc-shaped outer surfaces, the arcs being of greater length than the distance between any two of the partitions aforesaid, a port being formed in the side of the cylinder between the wings. 85

2. In a dust collector, the combination of a rotatable screen drum having radial longitudinal screen partitions arranged therein extending from the periphery part way toward the center; a stationary dusty air conveying cylinder about which the screen drum rotates; and a plurality of wings connected to and extending lengthwise of the cylinder 90 having arc-shaped outer surfaces, the arcs being of greater length than the distance between any two of the partitions aforesaid, a port being formed in the side of the cylinder 95 between the wings.

3. In a dust collector, the combination of a rotatable screen drum having radial longitudinal partitions arranged therein extending from the periphery part way toward the center; a stationary dusty air conveying cylinder about which the screen drum rotates; a plurality of wings connected to and extending lengthwise of the cylinder 100 having arc-shaped outer surfaces, the arcs being of greater length than the distance between any two of the partitions aforesaid, a port being formed in the side of the cylinder 105 between the wings; and a tank of water 110 into which said drum dips.

4. In a dust collector, the combination of a rotatable screen drum having radial longitudinal screen partitions arranged therein extending from the periphery part way toward the center; a stationary dusty air conveying cylinder about which the screen drum rotates; a plurality of wings connected to and extending lengthwise of the cylinder 115 having arc-shaped outer surfaces, the arcs being of greater length than the distance between any two of the partitions aforesaid, a port being formed in the side of the cylinder 120 between the wings; and a tank of water, 125 into which said drum dips.

5. In a dust collector, the combination of a rotatable screen drum having radial longitudinal partitions arranged therein extending from the periphery part way toward 130

- the center; a stationary dusty air conveying cylinder about which the screen drum rotates; a plurality of wings connected to and extending lengthwise of the cylinder having 5 arc-shaped outer surfaces, the arcs being of greater length than the distance between any two of the partitions aforesaid, a port being formed in the side of the cylinder between the wings; a rotary beater located within 10 said cylinder into which the dust laden air is led and from which it escapes into the cylinder; and means for leading water into the beater adjacent its axis.
6. In a dust collector, the combination of 15 a screen drum; a dusty air conveying cylinder extending axially of the drum and having an air port formed in its side; a rotary beater located within the cylinder co-axial therewith and out of alinement with the 20 port into which beater the dust laden air is led and from which it escapes into the cylinder; and means for leading water into the beater adjacent its axis.
7. In a dust collector, the combination of 25 a screen drum; a dusty-air conveying cylinder extending axially of the drum and having an air port formed in its side; a shaft extending axially of the cylinder; a rotary beater carried on said shaft within the cylinder; a pipe leading air to said beater, the 30 air passing from the beater into said cylinder; and a sleeve about said shaft adapted to convey water into the interior of the beater.
8. In a dust collector, the combination of 35 a rotatable horizontal screen drum; a dusty air conveying cylinder extending axially of the drum and having an air port formed in its side; a rotary beater located within the cylinder co-axial therewith and out of alinement 40 with the port into which beater the dust laden air is led and from which it escapes into the cylinder; means for leading water into the beater adjacent its axis; and a tank of water into which said screen drum 45 dips.

Signed at Toronto, Canada.
